BIN EXTENSION

Lloyd D. Slagell, Peoria, Ill., assignor to Creve Coeur Manufacturing Co., East Peoria, Ill., a corporation of Illinois

Filed July 19, 1968, Ser. No. 12,832

Term of patent 14 years

Int. Cl. D12—09, 99

U.S. Cl. D14—3

The figure is a perspective view showing the appearance of the inner and outer walls of my new design of a bin extension.

The dotted lines showing in the figure are for illustrative purposes only.

I claim:

The ornamental design for a bin extension, as shown and described.
